BELT OR TUBE TURNER

Bernard B. Chester, Kingston, N. Y.

Application May 1, 1937, Serial No. 140,258

1 Claim. (Cl. 223—40)

This invention appertains to new and useful improvements in apparatus for facilitating the inverting or turning of belts, ties, cuffs and various other tubular structures.

5 The principal object of the present invention is to provide a novel apparatus whereby a tubular article can be turned inside out in a single convenient operation.

Another important object of the invention is 10 to provide a device whereby tubular articles can be turned inside out regardless of whether the articles are open at their ends or closed.

Other important objects and advantages of the 15 invention will become apparent to the reader of the following specification.

In the drawings:—

Figure 1 represents a front elevational view of the apparatus.

Figure 2 is a side elevational view.

20 Figure 3 is a fragmentary vertical sectional view taken substantially on the line 3—3 showing an article thereon in the act of being turned.

Figure 4 is an enlarged sectional view on the line 4—4 of Figure 1.

25 Figure 5 is an enlarged horizontal sectional view on the line 5—5 of Figure 1.

Figure 6 is a side elevational view of the push rod with parts in section.

30 Figure 7 is a side elevational view of the blunt extension for the rod.

35 Referring to the drawings wherein like numerals designate like parts, it can be seen that numeral 5 represents a post or standard which can be mounted on a table or elsewhere in a convenient manner and this post has the split clamp 6 at its lower end portion projecting laterally thereof. This clamp includes the side lugs 7—7 held together by the screw 8 and this clamp structure bears on the split bushing 9 which surrounds the vertical barrel 10 adjacent its lower end and supports the barrel in a vertical position.

40 An L-shaped member 11 is secured to the upper portion of the post 5 and has an opening therethrough, thus serving as a guide for the chain 12.

45 A pair of guide brackets 13—14 are provided adjacent the intermediate portion of the post 5 and through these guide brackets 13—14 the push rod 15 is slidably disposed.

50 A collar 16 having a set screw 17 feedable therein is adapted to be fixed in any desired place on the push rod 15 by driving the set screw 17 against the rod 15. The collar 16 is provided with the socket 18 for receiving the laterally disposed end portion *a* of the pull rod 19 which extends downwardly through the guide 20 and is provided with a hand knob 21 at its lower end.

A coiled compressible spring 22 is interposed between the collar 16 and the guide bracket 11, and from the upper end of the rod 15 extends the aforementioned chain 12 to pass over the pulley 23 at the upper end of the post 5. This chain 12 passes downwardly through the guide eye 24 at the back side of the post 5 and connects to the upper end of the coiled extensible spring 25, which spring is anchored as at 26 to the back side of the post 5.

5 As is shown in Figure 6, the lower end of the rod 15 is provided with a threaded socket 27 for receiving the upper threaded and reduced end of either the attachment 28 or the attachment 29. The attachment 28 has the needle-like extension 30 for engaging the edge portion of a tubular article at one end of the article where the article is provided with open ends, while the attachment 29 is provided with a blunt end 31 which simply engages against the closed end of the tubular article as shown in Figure 3.

10 In operating the machine, it will be observed that the spring 25 will hold the rod 15 in the elevated position shown in Figure 2. The article to be inverted is now slipped over the barrel 10 and the lower end of the corresponding attachment 28 and 29 is engaged with the upper end of the article. The knob 21 is now grasped by the operator and pulled downwardly so as to cause downward movement of the rod 15. The rod 15 will 15 push the tubular article downwardly and through the lower end of the barrel 10, thus the article is inverted in a simple and convenient manner.

20 While the foregoing specification sets forth the invention in specific terms, it is to be understood that numerous changes in the shape, size and materials may be resorted to without departing from the spirit and scope of the invention as 25 claimed hereinafter.

30 What is claimed is:—

35 A device for turning tubular articles comprising a supporting member, a bracket carried thereby, a cylinder supported by the bracket, a push rod, brackets for supporting the same from the support in longitudinal alignment with the cylinder, a rod slidably supported on the support and having a handle at one end for sliding the last-mentioned rod, means for adjustably connecting the other end of the last-mentioned rod to the push rod, a pulley carried by the support 40 at that end which is remote from the end part carrying the cylinder, a spring connected to the rear face of the support and a flexible member having one end connected with the spring and its other end connected with the push rod, the flexible member passing over the pulley.
